UNITED STATES PATENT OFFICE.

GEORGE L. HESS, OF DENVER, COLORADO, ASSIGNOR TO HESS FLUME COMPANY, OF DENVER, COLORADO, A CORPORATION.

FLUME.

1,020,905.

Specification of Letters Patent. Patented Mar. 19, 1912.

Application filed October 20, 1911. Serial No. 655,732.

To all whom it may concern:

Be it known that I, GEORGE L. HESS, a citizen of the United States, residing at Denver, in the county of Denver, State of Colorado, have invented certain new and useful Improvements in Flumes; and I do hereby declare the following to be a full, clear, and exact description of the invention, such as will enable others skilled in the art to which it appertains to make and use the same.

This invention relates to flumes, and particularly that type employed in conveying water in irrigation.

The object of the invention resides particularly in the provision of an improved joint between the sections of a flume of the character named which will render the flume as a whole water tight and which at the same time will offer the least resistance to the flow of water through the flume.

A further object of the invention resides in the provision of a flume joint which will enable the sections of the flume to be connected together with ease and rapidity and which will afford the necessary strength to enable the flume to bear the loads and strains incident to its use.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a plan view of a fragment of a flume showing two flume sections connected together by the improved joint. Fig. 2, a section on the line 3—3 of Fig. 1. Fig. 3, a section on the line 2—2 of Fig. 1. Fig. 4, a transverse section through a modified form of the flume joint. Fig. 5, a longitudinal section through the modified form of flume joint illustrated in Fig. 4. Fig. 6, is an enlarged view of a fragment of Fig. 5 showing more clearly the various parts of the joint between the flume sections, and Fig. 7, a detail view looking at the end of the carrier beam and showing the manner of connecting same to the bolt strap which latter is attached to the outer clamping member disclosed in Fig. 3.

Referring to the drawings, 10 and 11 indicate adjacent sections of a flume which are of the usual semi-circular cross section. The adjacent ends of the sections 10 and 11 are of angular formation and each includes an arm 12 disposed at an obtuse angle to the body of the section and another arm 13 extending parallel to the body of the section, said last named arm constituting one end of the section.

The adjacent angular ends of the sections 10 and 11 seat in a groove 14 formed on the inner face of an outer clamping member 15 and have their outer terminal edges disposed in spaced relation. It will be noted that the groove 14 conforms in superficial shape to the angular ends of the sections 10 and 11 so that the arms 12 of said angular ends will contact with respective side walls of the groove while the arms 13 will contact with the bottom of the groove with the outer terminal edges of the arms 13 disposed in spaced relation. Also disposed within the groove 14 and clamping upon the angular ends of the sections 10 and 11 is an inner clamping bar 16, the inner face of which registers with the inner faces of the sections 10 and 11 while the outer face thereof conforms in superficial shape to the inner faces of the angular ends of the sections 10 and 11. Secured to each end of the outer clamping member 15 are bolt straps 17 which project through openings 18 in a carrier beam 19. This carrier beam 19 is of U-shaped cross section and the free ends of the arms thereof seat respectively in grooves 20 formed in the upper face of cam shoes 21. These cam shoes rest upon the ends of the inner clamping bar 16 respectively and have their upper faces in engagement with the free ends of the arms of the U-shaped carrier beam 19 as previously referred to. Each of the cam shoes 21 is provided at its outer end with an opening 22 through which respective bolt straps 17 pass when the joint is assembled.

From the foregoing construction it will be apparent that as the nuts on the bolt straps 17 are forced against the carrier beam the cam shoes 21 will force the ends of the inner clamping bar 16 outwardly and as a result distribute the force of such clamping action evenly which will render the joint water tight throughout. By constructing and mounting the inner clamping bar 16 so that

its inner face registers with the inner faces of the sections 10 and 11 the co-efficient of friction of the flume is reduced to a minimum and the carrying capacity of said flume correspondingly increased.

In the form of joint illustrated in Figs. 4 and 5 the outer clamping member 15 has bolted to its outer face a guide clip 23 having an arcuate cross section. Disposed in the channel of the clip 23 is a carrier rod 24 the terminals of which are reduced and threaded and passed through the openings 22 and 18 in the cam shoes 21 and carrier beam 19 respectively. The threaded ends of the carrier rod 24 are provided with the usual nuts whereby said rod may be forced against the clip 23 to produce the necessary clamping action upon the inner clamping bar 16 and the outer clamping member 15. The use of the carrier bar 24 is resorted to when it is desired to provide for sustaining extremely heavy loads in the flume.

The flume sections 10 and 11 are strengthened by having struck up therefrom at each side longitudinally disposed reinforcing ribs 10' and 11' respectively. These reinforcing ribs 10' and 11' terminate short of the ends of respective flume sections so as to not interfere with the joint between adjacent sections.

What is claimed, is:—

1. The combination of a pair of flume sections having their adjacent ends formed with angular and horizontal portions and their adjacent terminal edges disposed in spaced relation, and inner and outer clamping bars having angular and horizontal bearing surfaces corresponding to the angular

and horizontal portions of the flume section ends.

2. The combination of a pair of flume sections having their adjacent ends formed with angular and horizontal portions and their adjacent terminal edges disposed in spaced relation, and inner and outer clamping bars having angular and horizontal bearing surfaces corresponding to the angular and horizontal portions of the flume section ends, said inner clamping bar having its inner face in registration with the inner faces of the flume sections.

3. The combination of a pair of flume sections, fastening means securing the adjacent ends of said sections together, said fastening means including inner and outer clamping members receiving the ends of the sections between them, a carrier bar extending contiguous with the outer clamping member and disposed against the outer face of the latter, and means for locking the clamping bar against lateral movement relatively to the outer clamping member.

4. The combination of a pair of flume sections having their adjacent ends formed with angular and horizontal portions and inner and outer clamping members having angular and horizontal bearing surfaces corresponding to the angular and horizontal portions of the flume section ends.

In testimony whereof, I affix my signature, in presence of two witnesses.

GEORGE L. HESS.
